UNITED STATES PATENT OFFICE.

MORRIS FULLER BENTON, OF PLAINFIELD, NEW JERSEY, ASSIGNOR TO AMERICAN TYPE FOUNDERS COMPANY, OF JERSEY CITY, NEW JERSEY, A CORPORATION OF NEW JERSEY.

AUTOMATIC METAL-FEED FOR TYPE-CASTING MACHINES.

1,272,193.

Specification of Letters Patent.

Patented July 9, 1918.

Application filed June 6, 1916. Serial No. 102,057.

To all whom it may concern:

- Be it known that I, MORRIS FULLER BENTON, a citizen of the United States, residing at Plainfield, Union county, and State of New Jersey, have invented and discovered certain new and useful Improvements in Automatic Metal-Feeds for Type-Casting Machines, of which the following is a specification.
- 10 The present invention relates to apparatus for feeding pigs of metal to melting pots, and consists in the arrangements and combinations of elements hereinafter described and particularly set forth in the accompanying claims.

The invention has for its purpose to provide an arrangement for feeding pigs of metal to the melting pots of type casting machines in a manner which will insure constancy of level of the molten mass, and wherein the pigs are initially pre-heated directly from the furnace before entering the pot, to the end that the temperature of the molten metal will not be affected by the pig being fed thereto.

The further purpose of the invention resides in that solid metal, in pigs of different sizes and rough cast, may be fed into the melting pot at exactly the rate of speed necessary for proper working, without requiring any adjustments of parts, and wherein the moving parts that require lubrication are removed from the deteriorating influences of the heat and fumes from the furnace.

35 The invention is disclosed by way of illustration in the accompanying drawings, wherein—

Figure 1 is a front elevational view of a melting furnace showing the application of the present invention, with parts broken away and in section for clearness.

Fig. 2 a side elevational view thereof,

Fig. 3 a transverse sectional view with parts in elevation,

45 Fig. 4 a horizontal sectional view through the gearing feed control,

Fig. 5 a longitudinal sectional view taken on the line 5—5 of Fig. 4,

Fig. 6 a side elevational view of the equipment,

Fig. 7 a perspective view of the same, and

Fig. 8 a detail top view of the melting pot.

Referring to the construction in further detail, 1 represents the melting pot of any

melting furnace, which may be heated, as usual, by one or more burners within the furnace 2 to keep the contained metal A in a molten condition, and said furnace is constructed with outlet openings 3, through which a varying portion of the products of combustion pass after the manner shown by the arrows in Fig. 3. The remainder of the products of combustion pass up through holes 53, partially surrounding and extending through the rim of the melting pot. (See Fig. 8).

A yoke or frame 4 is suitably mounted on the furnace and supports a bracket or frame 5 that is provided with a pair of apertured lugs 6 and 7 providing guides for the vertically disposed and gravity actuated bar 8 that is adapted to carry a pig of metal B. Said pig is formed with a head portion C that fits within the slotted member 9 mounted on the lower end of the bar 8; and said bar is adapted to be lowered progressively with and at the rate of consumption of the molten metal, in a manner to be presently described.

A shield 10, preferably constructed of sheet metal, is adapted to partially inclose the pig being fed to the molten mass, as shown in Fig. 3, and, with said pig, provides a flue, or chimney, to direct the products of combustion issuing from the outlet opening 3, against the inclosed sides of said pig, to the end of partially fusing, or pre-heating, the pig as it is fed to the molten liquid or point of complete fusion, and thereby maintaining a constant mean temperature of the molten mass, *i. e.* to guard against the periodic cooling of said mass, as would be the case were the pig fed, step by step, to the melting pot at the temperature of the surrounding atmosphere. The shield 10 is hingedly mounted to the furnace at 11, and is formed with an open side to allow it to readily pass the extension 12 of the melting pot when moving into and out of operative position; and above said pot the opening is of just that width to easily embrace the pig on one side.

It will be seen from the above that the pig forms part of one side of this chimney and when first put in, it fills the opening in the side of the chimney, when same is in operative position, and under these conditions the maximum amount of heat is drawn

through the holes 3 to pre-heat the pig. As the pig is fed into the melting pot, less and less heat is necessary and as the upper end of the pig gradually falls below the top of the chimney, it uncovers more and more of the side opening therein, thus reducing the draft and the amount of heat drawn through said holes 3, thus maintaining a substantially uniform temperature around 10 said pig and keeping it in a uniform state as relating to its fusibility at the point adjacent to the molten metal. If it were not for this arrangement, the last part of the pig would be melted off its support before it 15 reached the level of the molten metal, and it would drop out of the gripper head 9 into the pot.

The pig supporting bar is connected, by a pin 13 at its lower end, to one end of the 20 chain 14 that passes over a sheave 15 journaled in suitable bearings on the guide member 7 of the frame 5; and said bar has a channel or groove 16 for substantially its full length and within which the sheave 15 25 and the lowering chain portion fit, as indicated in Fig. 1. The purpose of this construction is to hold the bar 8 against rotation, thus lowering the pig steadily into the melting pot 1 and, by having the chain 14 30 connected to the bar 8 in the manner stated, prevents any tendency of side-thrusts on the bar and allows it to descend freely.

The chain 14 passes around a sheave 17 and enters the gear casing 18 where it is 35 wound upon the sheave 19 (see Fig. 4) journaled on the shaft 20 in said casing. The sheave 19 is adapted to be intermittently rotated under the weight of the pig B and its supporting bar 8, and such movements 40 are adapted to be controlled from a clock-work mechanism that is controlled by a float 21 (see Fig. 3) in the molten mass A. The sheave 19 is constructed as a double sheave (19 and 19^a), and the sheave portion 19^a 45 thereof has a chain 14^a wound thereon in the direction reverse to that of the chain 14, whereby said sheave (19) may be rotated to rewind the chain 14.

The clock-work mechanism consists of a 50 ratchet wheel 22 secured to the pinion 23 that is fixed to rotate with the shaft 20, and said ratchet is engaged by the pawl 24 pivotally mounted on the side of the sheave 19, as shown in Figs. 4 and 5. The pinion 23 55 meshes with a smaller pinion 25 connected to a larger pinion 26, and which, in turn, gears with a smaller pinion 27 that is fixed to rotate with the toothed wheel 28 when said toothed wheel is engaged by the double 60 pawl or verge 29 that is pivotally mounted on the shaft 30 that supports the gear wheels 25 and 26. An arm 31 (see Figs. 6 and 7) 65 is dependently mounted on said double pawl and has a lateral extension 32 adapted to engage with the pointed end 33 of the verge

bar 34 that is actuated by the float supporting lever 35 journaled on the support 36.

In operation the apparatus works after the following manner: Assuming the level of the molten metal to have fallen, the float 21 will be lowered, consequently raising the bar 34 from engagement with the verge arm 32. The verge 29 will now be free to vibrate on its pivot 30 and for each double-vibration the toothed wheel 28 will be allowed to turn a distance of one tooth, due to the weight of the pig B and bar 8 pulling on the chain 14 and turning the several gear wheels, and, the pig having thus been lowered into the molten metal, the level of this metal will 75 rise and with it the float 21. This will cause the verge bar 34 to descend and engage the verge arm 32 and thus check the further descent of the pig until the level of the molten metal falls again.

In order to place a new pig in position, the operator throws back the shield or chimney 10 and pulls down on chain 14^a on the sheave 19^a until the feed bar 8 has been raised to its uppermost position, when the 90 head of the new pig is inserted in the recess of the member 9. The shield is then pushed back into vertical position and the rewinding chain 14^a is released. The bar 8 carries a collar 38 which comes into contact with the 95 upper guide member 6 and indicates the time for inserting a new pig.

It is obvious that those skilled in the art may vary the details of construction and arrangement of parts without departing from the spirit of my invention, and therefore I do not wish to be limited to such features except as may be required by the claims.

Having thus fully described my said invention, what I claim as new and desire to 105 secure by Letters Patent, is:

1. The combination with a melting pot for holding a supply of molten metal, and means for feeding a pig of metal thereto, of a shield adapted to inclose the pig and extend to below the metal holding pot and provide a flue to conduct the products of combustion up around said metal holding pot and pig, and heating means located beneath said pot, substantially as set forth.

2. The combination with a melting pot for holding a supply of molten metal, and means for feeding a pig of metal thereto, of a heating device located beneath said metal holding pot, and a shield extending from below said metal holding pot up around said pig inclosing three sides thereof, the pig itself forming the fourth side, whereby the heat is conducted from said heating device up around said pig above its 125 part which projects into said metal holding pot, substantially as set forth.

3. The combination with a melting pot having a combustion chamber provided with an outlet opening and means for feeding a 130

pig of metal to the molten mass, of a shield adapted to partly inclose the pig and form a flue to receive the products of combustion from said outlet opening, substantially as 5 set forth.

4. The combination with a melting pot having a combustion chamber provided with an outlet opening and means for feeding a pig of metal to the molten mass, of a 10 shield comprising a sheet metal plate constructed to form a flue, said flue communicating at one end to receive the products of combustion from the outlet opening and through which the pig is passed, and means 15 for mounting said shield whereby the same may be moved into and out of position, substantially as set forth.

5. The combination with a melting pot having guides mounted thereon, of a gravity 20 actuated bar mounted in said guides and adapted to carry a pig of metal, and automatically actuated means for controlling the feed of said bar, substantially as set forth.

6. The combination with a melting pot 25 having guides mounted thereon, of a gravity actuated bar mounted in said guides and adapted to carry a pig of metal, a flexible member connected with and supporting said bar, and automatically actuated means 30 for controlling the movement of said flexible member to feed said bar, substantially as set forth.

7. The combination with a melting pot 35 having guides mounted thereon, of a gravity actuated bar mounted in said guides and adapted to carry a pig of metal, a flexible member connected with and supporting said bar, a float adapted to be supported by the molten mass, and means connecting said 40 float with the flexible member for automatically controlling the movement of the flexible member to feed said bar, substantially as set forth.

8. The combination with a melting pot 45 having guides mounted thereon, of a gravity actuated bar mounted in said guides and adapted to carry a pig of metal, a flexible member connected with and supporting said bar, a sheave on which said flexible member 50 is wound, an escapement mechanism associated with the sheave, a float adapted to be supported by the molten mass, and means connecting said float with the escapement for automatically controlling the 55 movement of the flexible member to feed said bar, substantially as set forth.

9. The combination with a melting pot 60 having guides mounted thereon, of a gravity actuated bar mounted in said guides and adapted to carry a pig of metal, a flexible member connected with and supporting said

bar, a sheave on which said flexible member is wound, a gearing connected to be driven by said sheave, an escapement associated with the gearing, a float adapted to be supported by the molten mass, and means connecting said float with the escapement for automatically controlling the movement of the flexible member to feed said bar, substantially as set forth. 65

10. The combination with a melting pot having guides mounted thereon, of a gravity actuated bar mounted in said guides and adapted to carry a pig of metal, a flexible member connected with and supporting said 70 bar, a sheave on which said flexible member is wound, means for automatically controlling the unwinding of the sheave to feed said bar, a second sheave, and a flexible member wound on said second sheave for 80 rewinding the flexible member on the first sheave to raise the pig supporting bar, substantially as set forth.

11. The combination with a melting pot 85 having a frame mounted thereon provided with guides, of a gravity actuated bar mounted in said guides, said bar provided with a longitudinally disposed slot, a sheave journaled on the frame and fitting within the slot of said bar, a flexible member passing over the sheave and fitting within said slot and secured to the bar at the lower end thereof, and means for automatically controlling the movement of the flexible member to feed said bar, substantially as 90 set forth.

12. The combination with a melting pot 100 having a frame mounted thereon provided with guides, of a gravity actuated bar mounted in said guides and adapted to carry a pig of metal, a sheave mounted on said frame, a chain passing over said sheave and connected to said bar at the lower end thereof, a casing, a sheave journaled in said casing and having said chain wound thereon, a detent mechanism associated with said casing sheave, a float adapted to be supported by the molten mass, a lever connecting said float with the detent mechanism 105 for automatically controlling the movement of the chain to feed said bar, and means for rewinding the chain on said casing sheave to raise the pig supporting bar, substantially as set forth.

In witness whereof, I have hereunto set 110 my hand and seal at Jersey City, New Jersey, this 25th day of May, A. D. nineteen hundred and sixteen.

MORRIS FULLER BENTON. [L. S.]
